Joseph G. Lamb: Cincinnati, Ohio.

Letters Patent No. 386. Dated June 17, 1851.

The schedule referred to in these Letters Patent and making part of the same:

To all whom it may concern:

Be it known that I, Joseph G. Lamb of Cincinnati, in the County of Hamilton & State of Ohio, have invented or produced a new ornamental Design for Premium Cooking Stoves, and I do hereby declare that the following is a full & exact description & the annexed drawings are a correct representation of the same, To wit, Fig I.A is a front view of the whole stove. Fig I.B. plan of front cut through the center — Fig II.A is a side view of the whole stove. Fig II.B. is plan of side cut through center of doors. Fig III.A — Back — Fig III.B. plan of Back. Fig IV. Cornice & top mouldings. Fig V. Border around bottom or hearth plate — Fig VI. Base & bottom moulding. Fig VII. Corners — Fig VIII. enlarged section of centers of door panels — corresponding figures refer to corresponding parts.

Having thus fully described and shown the aforesaid design, what I claim as my invention and desire to secure by Letters Patent, is the combination and arrangement of the above described & represented shapes mouldings & ornaments, substantially as herein shown —
